UNITED STATES PATENT OFFICE

ANE PIETER SCHAT, OF WASSENAAR, NEAR THE HAGUE, NETHERLANDS

MEANS FOR HANDLING LIFEBOATS

Application filed June 26, 1925, Serial No. 39,805, and in Great Britain March 26, 1925.

My present invention relates to means for handling a life boat, one object of the invention being to facilitate both the launching and the recovering of the boat, another object being to protect the boat against coming into direct contact with the side of the vessel and thereby prevent it from tipping or canting on the high side of the ship's hull and from being damaged should it be smashed 10 against the ship due to the rolling thereof.

A leading feature of my invention consists of a pair of runners arranged to be detachably secured to the inboard side of the lifeboat to prevent the lifeboat from contacting 15 with the hull of the ship as it is raised and lowered thereon.

The invention consists in certain novel features of construction and arrangement of parts as will be hereinafter described and 20 claimed, reference being had to the accompanying drawings in which:

Fig. 1 is a side elevation of one of my improved devices as it appears in operative position on a lifeboat mounted on ship deck. 25 Fig. 2 is a broken plan view of the boat shown in Fig. 1, the skids or runners being shown principally in dotted lines.

Fig. 3 is a sectional view taken through one of the skids and a sloping bar of the running way on which the boat is supported on deck. 30

Fig. 4 is a broken vertical section of the gunwale of the boat on its inboard side, showing the means of clamping a skid thereto.

Fig. 5 is a side elevation of Fig. 4; and, 35 Fig. 6 is a broken top plan view of the gunwale of the boat at the upper end of the skid, showing the clamping mechanism in the position it occupies when the skid is to be detached from the boat, the upper end of the 40 skid being shown in section.

A number of prior constructions have been devised exclusively for exceptional cases, for instance, for leaving a sinking or a beached ship, but they do not sufficiently meet 45 the requirements of the usual boat drill, which is often held once every fortnight and during which the boats and their cradles or sleds should be tried out and rowing or sailing tests held. With known constructions, it 50 takes a whole merchant's steamer deck crew

to restore the cradles and the boats in position ready to be used again in an emergency case.

In accordance with my present invention, I simply provide the boat, at its inboard side, 55 with one or more pieces of T-iron fitted with their flanges flat against the boat's side, so that, when the boat is launched, only the relatively sharp edge of the body portions of the T-irons can contact with the hull of the vessel. Hereby the contact surface area and, as a consequence, the frictional resistance and the canting moment are reduced to a minimum. 60

As will be seen from Figs. 1 and 2, the boat 20 is provided with two members (hereinafter termed "skids") 49, 50 each consisting of a piece of T-iron bent to fit with its flange flat against the inboard side of the boat. Each skid is provided with a bearing 70 51 for the keel of the boat and further with suitable means for clamping the skid to the gunwale of the boat. For each skid there is provided on deck an outwardly sloping way 75 in the form of a frame 52 provided with pairs of rollers 53 for the flange of the skid to run on, see Fig. 15. At its top end each skid 50 carries an eccentric 56 for clamping engagement with the upper edge or gunwale of the boat. At its outer side this eccentric has a 80 pivot or journal 54 which pivotally engages the upper end of the skid; and at its inner side it has a forwardly extending right-angled extension 57 located just beyond the inner edge of the gunwale. The operating 85 handle or lever 55 of the eccentric extends rearwardly from the eccentric above the top edge of the boat, being in the same horizontal plane as the forward extension or finger 57. The lever 55 and the finger 57 are so arranged 90 relatively to the eccentric that when said handle and finger are in the horizontal position, as shown in Fig. 5, the eccentric is in its low position with the handle and finger occupying a plane slightly above the top edge 95 of the boat, so that the eccentric can be moved laterally inward into a position above the upper edge of the gunwale, as shown in Fig. 6; or it can be moved outwardly to disengage the skid from the boat.

However, when the cam 56 and the parts connected therewith are in the position shown in full lines in Figs. 5 and 6 of the drawings, it will be seen that if the handle 55 is elevated, the high side of the eccentric will be 5 forcibly pressed into engagement with the top edge or gunwale of the boat, and the finger 57 will be turned downwardly at the inner side thereof, so that the upper end of 10 the skid will be positively held and also locked against lateral movement away from the boat.

When the boat is to be launched, the same is allowed to slide downwardly along the inclined ways 52 after its supporting means 15 have been moved out of the way. During its movement over the ways 52, the bottom sides of the flanges of the T-skids are supported by the rollers 53, but when the boat is over 20 the side, the sharp edges of the skids serve to guide the boat over the hull of the vessel. When the boat is waterborne, the skids can easily be released and removed in the manner described hereinbefore and, if desired, taken 25 into the boat. Preferably, also in this installation a roller or tube (not shown) is provided at the edge of the ship's deck.

Instead of skids having a substantially 30 T-shaped cross-section, I may of course use skids having an angular or triangular cross-section, provided that these be secured to the boat in such a manner that a sharp edge thereof is adapted to slide over the ship's hull.

It is evident that my novel skids, owing 35 to their low weight and simple construction, can very easily be handled and replaced.

Having now particularly described and ascertained the nature of my said invention and in what manner the same is to be performed, I declare that what I claim is:—

1. In a device for launching lifeboats, a 40 skate formed of a piece of metal bent to fit the profile of the boat, and provided on its outer or convex side with an edge for contacting 45 with the hull of the ship when the boat is being launched, and on its inner or concave side being provided with a flat face to prevent the device from rocking laterally on the boat, and means for detachably securing the 50 device to the boat.

2. In a device for launching a lifeboat, a 55 skate formed of a piece of metal having its upper end portion bent to fit the profile of the boat, and having the portion between its 60 ends straight, the device being provided on its inner or concave side with a flat face to hold it against rocking laterally on the boat, and on its convex side being narrowed to an edge portion for engagement with the hull of 65 the ship; and means for detachably securing the device to the boat.

3. In a device for launching lifeboats, a 70 skate formed of a piece of metal having its upper end portion bent to fit the profile of the boat, and having the portion between its ends

straight, the device being provided on its inner or concave side with a flat face to hold it against rocking laterally on the boat, and on its convex side being narrowed to an edge portion for engagement with the hull of the ship; and means for detachably securing the device to the boat, said device having means on its lower inner face for engagement with the keel of the boat, and on its extreme upper end having means for engagement with the gunwale of the boat, said means being arranged for vertically adjusting said upper end of the skate upwardly off the gunwale of the boat, whereby to draw the skate into binding engagement with the boat. 75

4. In a device for launching lifeboats, a 80 skate formed of a piece of metal having its upper end portion bent to fit the profile of the boat, and having the portion between its ends straight, the device being provided on its inner or concave side with a flat face to hold it against rocking laterally on the boat, and on its convex side being narrowed to an edge portion for engagement with the hull of the ship; and means for detachably securing the device to the boat, said device having means on its lower inner face for engagement with the keel of the boat, and on its extreme upper end having an eccentric cam 85 for clamping engagement with the gunwale of the boat. 90

5. In a device for launching lifeboats, a 95 skate formed of a piece of metal having its upper end portion bent to fit the profile of the boat, and having the portion between its ends straight, the device being provided on its inner or concave side with a flat face to hold it against rocking laterally on the boat, and on its convex side being narrowed to an edge portion for engagement with the hull 100 of the ship; and means for detachably securing the device to the boat, said skate being arranged on its lower inner face for engagement with the keel of the boat, and on its extreme upper end having an eccentric cam 105 for clamping engagement with the gunwale of the boat, said eccentric cam having an operating lever arranged to be swung into a horizontal position on the top of the gunwale in parallelism therewith when the eccentric cam is in its upper or inoperative position, and upwardly into a vertical position when the cam is in its operative or clamping position; and a hook lever 110 overhanging the inner edge of the gunwale in the same transverse plane as the operating lever and arranged to extend downwardly when the cam is in its clamping position on the gunwale, whereby said hook lever holds the upper end of the skate against outer lateral movement away from the boat. 115

6. In a device of the character described, a 120 lifeboat skate curved at its upper end to conform to the curvature of the boat, said skate having its main section formed of flat iron 125

bent edgewise, whereby to present an edge to the ship's side as the boat descends, said
5 skate having its inner or concave side pro-
vided with a flat section disposed at right
angles to said main section; whereby to hold
the main section at right angles to the lon-
gitudinal extent of the boat, and to spread
the shock over a large surface when the life-
boat is smashed against the side of the ship;
10 and means for detachably securing the skate
to the boat.

Dated this 9th day of April, 1925.

In testimony whereof I affix my signature.

ANE PIETER SCHAT.
